(57) **CLAIM**

The ornamental design for a terminal device, as shown and described.

DESCRIPTION

FIG. 1 is a front perspective view of a terminal device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in FIGS. 1-3 and 5-7 that are immediately adjacent to the areas included in the claim, and define unshaded regions, represent the bounds of the claim. The broken lines form no part of the claimed design.
